(57) **CLAIM**

I claim the ornamental design for a portable computer, as shown and described.

DESCRIPTION

FIG. 1 is a first rear perspective view of a portable computer according to the present invention;

FIG. 2 is a second rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines in the drawings illustrate portions of the portable computer which form no part of the claimed design. In addition, the dash-dot-dash broken lines in FIGS. 1, 2 and 4 represent boundaries of the claimed design that that form no part of the claimed design.
